UNITED STATES PATENT OFFICE

PETER C. WEGO, OF ST. PAUL, MINNESOTA

TRAY ELEVATOR

Application filed February 26, 1927. Serial No. 171,254.

This invention relates to an elevator, particularly, although not exclusively, adapted for raising and lowering dish trays from one floor or level to another in restaurants and 5 arranged to coact with means for automatically removing trays from downwardly moving tray supports.

As far as I am aware, the elevators heretofore provided for such work have been 10 necessarily complicated and expensive and have had the further disadvantage of requiring an excessive amount of space for installation. Thus, as the space available for an elevator is often very limited, the elevators heretofore provided have been unsuited 15 for general use.

It is my object to provide a novel and inexpensive elevator, which is arranged to occupy a minimum of space. A further object 20 is to provide in an elevator of this kind a novel arrangement of tray carriers and coacting guides whereby smooth and continuous travel of the tray supports is insured and friction is reduced to a minimum.

25 This invention also includes certain other novel features of construction, which will be more fully pointed out in the following specification and claims.

In the drawings, Figure 1 is a side elevation of my improved elevator; Fig. 2 is a horizontal section through the same, taken on the line 2—2 of Fig. 1 and showing a suitable arrangement of driving mechanism for operating the elevator; Fig. 3 is a front elevation of one of the tray supports and carrier therefor; Fig. 4 is a side view of a tray support and carrier; Fig. 5 is a plan view of the same; Fig. 6 is a horizontal section through an elevator having an alternate form of tray 35 support, adapted for use with simplified tray removing mechanism and Fig. 7 is a front view of an elevator having an alternate arrangement of guides and supporting sprockets for the chain.

40 As illustrated, my improved elevator has a single, endless chain 8 to which a series of spaced tray supports 9 are secured at suitable intervals. A guard plate 10 is provided on each tray support to extend between the tray 45 and chain. Each tray support is rigidly se-

cured to a traveling carrier consisting of a vertical plate or frame member 11, two rearwardly extending frame members 12, each secured to the chain 8 and a series of anti-friction wheels 13, adapted to run upon the 55 guides hereinafter described. Each rearwardly extending or transverse frame member 12 is preferably constructed in the form of a hollow rectangle, the front side of which is connected to the longitudinal member 11 and the rear side to the chain 8. Each lateral side of each member 12 carries a pair of the 60 wheels 13, so that each carrier has eight wheels adapted to engage suitable guides. The members 12 of each carrier are pivotably secured to the member 11, one of said 65 members 12 being attached to the plate 11 by a bolt 14, which is free to slide in a slot 15 in said plate. It will be evident that this slot 15 permits movement of one of the members 12 toward and away from the other.

Extending parallel to the chain 8 is a pair of guides for the tray supports having inwardly extending flanges 16 upon which the 70 wheels 13 operate. Each guide has a rearwardly extending flange 18 which is secured by horizontal arms 17 to vertical frame members 19 of the elevator. One of these frame members 19 is arranged back of each vertical run of the chain and transverse members 20 75 connect the members 19.

In the preferred construction, shown in Figures 1 and 2, the chain 8 is supported at the upper and lower ends of the elevator respectively upon large sprocket wheels 21 and 22. The upper sprocket wheel 21 is supported upon a shaft 23 having suitable bearings in the elevator frame and the lower sprocket wheel 22 is fixed upon a shaft 24, 80 adapted to be driven through a train of gears 25 by an electric motor 26 (see Fig. 2). It will be noted that the guide flanges 16 extend in a vertical plane and have arcuate portions which are concentric with the chain 8 where it passes over the periphery of the sprocket 85 wheels 21 and 22. These guide flanges are continuous or endless so that the wheels 13 are retained in contact therewith during the entire travel of the tray carrier. It will also be noted that the flanges 16 extend in the 90 95 100

same plane throughout their length, including the arcuate portions at the upper and lower ends of the elevator.

Each of the tray supports 9 in the preferred construction shown in Figs. 1 and 2 is substantially U-shaped in plan view, having a pair of parallel arms 9^a which support the tray and project toward the front of the elevator. To properly center the trays upon these arms 9^a, I provide side walls 27, between which the tray carriers pass in their downward movement. These walls 27 are supported upon the transverse frame members 20. To automatically remove the trays from the carriers 9 at the lower end of the elevator, a bed of rollers 28 is arranged to project from a support 29 between the arms 9^a and the tray carrier. Another roller 30 is also provided to convey the trays from the rollers 28 to a suitable belt 31 passing over a drum 32. The bed of rollers 28 and 30 may be arranged to slope away from the elevator to remove the trays by gravity, but in the construction shown in Figs. 1 and 2, I have illustrated suitable mechanism for positively rotating the rollers and thus insure quick removal of the trays deposited on the rollers 28. This driving mechanism consists of a series of bevel gears 33 severally mounted on axial shafts of the rollers 28 and coaxing beveled gears 34 fixed on a transverse shaft 35. A gear 36 on the shaft 35 is driven by a gear similar to the gear 33 which is fast on the supporting shaft of the roller 30, the latter roller being driven at its opposite end through suitable gears 37 connected with an electric motor 38. The belt 31 may also be positively operated to convey the trays away from the elevator.

In the arrangement of tray supports shown in Fig. 6, the arms 39 of each tray support extend toward one lateral side of the elevator, so as to receive between them a simplified "take off" consisting of a belt 40 running upon a drum 41. Suitable transverse members 42 connect each pair of arms 39 to form a rigid structure. These members 42 in their downward travel pass the end of the belt 40 beyond the drum 41. The tray supports are arranged to carry the trays with their centers of gravity to the left of the axis of the drum 41 as seen in Fig. 6.

In the form of elevator shown in Fig. 7, a pair of sprocket wheels 43 are substituted for each of the wheels 22 and 21 of the preferred construction. This form of elevator permits the use of wider tray supports and smaller sprocket wheels and is employed where space of greater width is available for installation of the elevator, but where the longitudinal space at the ends of the elevator is more limited. As shown in Fig. 7, the guide flanges 16^a, adjacent to the chain 8 where it passes over the sprocket wheels 43, are formed in arcs which are concentric with the adjacent sprocket wheels. The take off rollers 28,

shown in Fig. 7, may be driven by extending the shaft 35 toward the vertical center plane of the elevator and driving said shaft through a suitable gear 44 thereon. Otherwise, the elevator of Fig. 7 may be made similar to that shown in Figs. 1 and 2.

Operation

In operation, the chain 8 may be continuously driven in the direction indicated by arrows in Figs. 1 and 7 to transport trays filled with dishes or the like from an upper level or floor 45 to the belt 31 or 40. A loaded tray may be placed on each of the supports 9 as soon as it arrives at its horizontal position between the upper ends of the walls 27. The guard plates 10 prevent the contents of the trays from projecting towards the chain where there would be danger of striking parts of the elevator frame during the travel downward. Thus, each tray is lowered between the guides 27 until the arms 9^a of the tray support pass the rollers 28 when the tray is deposited upon said rollers. As soon as a tray is deposited upon the upper peripheries of the rollers 28, it is conveyed thereby successively to the roller 30 and the belt 31 and is carried by the latter out of the way of succeeding trays.

The operation of the arrangement shown in Fig. 6 is similar to that above described except that the downwardly moving tray supports 39 deposit the trays directly upon the belt 40, which conveys them away from the elevator. The chain 8 of the elevator shown in Fig. 7 may be driven by power applied to one of the shafts supporting the sprockets 43. The tray supports 9 with their supporting carriers are thus traversed under the guidance of the flanges 16^a.

To insure against breakage in case a tray is allowed to remain on the rollers 28 or belt 40, an automatic stop for the motor may be provided. A suitable stop for this purpose is described and claimed in United States Patent No. 1,422,091 to W. T. Donaldson, dated July 11, 1922.

It will be noted that the carrier guides extend throughout their length in uniform spaced relation to the chain 8 so that there is no tendency for the tray carriers of light weight to catch when passing between the curved portions of the guides, as would be the case if the usual, eccentrically disposed guides were employed. Further, the proper horizontal position of the tray supports is maintained while they are passing along the straight portions of the guides because of my peculiar arrangements of carriers. Thus, the tray supports are rigidly secured to the carrier members 11, which are of ample length and always maintain their position substantially longitudinally of the chain 8, while the pivoted members 12 permit movement of the wheels 13 to conform to the guide flanges 16^a.

These features reduce friction to a minimum.

My invention has the further advantage of being adapted to raise a series of trays along one longitudinal run of the chain 8 and at the same time to lower another series at the other side or run of the chain. When so used, the trays may be manually removed from the rising supports 9 by an attendant stationed upon the floor 45. To insure 10 against breakage, which would result if a tray were allowed to remain on a carrier as it passed into the curved guides at the top, any suitable or well known switch, operable by engagement with the trays, may be placed 15 near the upper end of the vertical guides and connected in the motor circuit. Further, when the elevator is used for raising as well as lowering trays, the guard plates 10 may be formed to extend at both sides of the supports 9 instead of at one side as illustrated. 20

Having described my invention what I claim as new and desire to protect by Letters Patent is:

1. In an elevator, the combination with 25 sprocket wheels and an endless chain operable upon said wheels in a vertical plane, of a stationary guide having front and back surfaces extending in parallel relation to said chain and having arcuate portions adjacent 30 to said wheels arranged substantially concentrically therewith, a carrier secured to said chain, means on said carrier revoluble about axes parallel to said surfaces and continuously engaging the front and back surfaces 35 of said guide, driving means for said chain and a support for the material to be conveyed disposed on said carrier to project adjacent to the faces of said wheels at one side only of the elevator during the operation 40 of said chain.

2. In an elevator having a frame and sprocket wheels at the upper and lower ends of said frame, a single endless chain operable upon said wheels in a vertical plane, a 45 stationary guide having front and back surfaces extending in parallel relation to said chain, carriers secured to said chain at spaced intervals, said carriers having means for continuously engaging the front and back surfaces 50 of said guide, said means being revoluble about axes parallel to said surfaces, driving means for said chain and a support for the material to be conveyed disposed on each carrier to project adjacent to the faces of said 55 wheels at one side only of the elevator during the operation of said chain.

3. In an elevator, the combination with 60 sprocket wheels and an endless chain operable upon said wheels in a vertical plane, of a stationary guide having front and back surfaces extending in parallel relation to said chain and in a plane in front of the plane of said chain, said guide having arcuate portions adjacent to said wheels arranged substantially concentrically therewith, carriers

secured to said chain at spaced intervals, said carriers having means for continuously engaging the front and back surfaces of said guide, said means being revoluble about axes parallel to said surfaces, driving means for 70 said chain and a support for the material to be conveyed disposed on each carrier to project in front of the plane of said guide and at one side only of the elevator.

4. In an elevator, the combination with a 75 pair of guides disposed in a vertical plane, said guides each having two longitudinal, straight portions, a carrier mounted between said guides, said carrier having a longitudinal member, spaced, transverse members secured to said longitudinal member and a wheel arranged on each lateral side of each of said transverse members, said wheels being disposed to run upon said guides, power driven means for traversing said carrier upon 80 said guides and means projecting from said carrier to support the material to be conveyed. 85

5. In an elevator, the combination with a 90 pair of guides disposed in a vertical plane, said guides having vertically extending straight portions and arcuate upper and lower portions, an endless chain operable in a plane in the rear of said guides, a carrier mounted between said guides and secured to said chain, said carrier having a longitudinal member, spaced, transverse members secured to said longitudinal member and a pair of wheels arranged on each lateral side of each of said transverse members, the wheels of each pair being disposed to receive one of 95 said guides between them, power driven means for operating said chains to traverse said carrier upon said guides and means projecting from said carrier in front of said guides to support the material to be conveyed. 100

6. In an elevator, the combination with a 110 pair of guides, a carrier mounted between said guides, said carrier having a longitudinal member, spaced, transverse members pivotally secured to said longitudinal member and a wheel arranged on each lateral side of each of said transverse members, said wheels being disposed to run upon said guides and power driven means for traversing said carrier upon said guides. 115

7. In an elevator, the combination with a 120 guide disposed in a vertical plane, a carrier mounted adjacent to said guide, said carrier having a longitudinal member spaced, transverse members pivotally secured to said longitudinal member and pairs of wheels arranged on said transverse members to run upon the front and rear faces of said guides, power driven means for traversing said carrier upon said guide and a tray support rigidly secured to said longitudinal member and arranged to project in front of said guide in planes perpendicular thereto. 125

8. In an elevator, the combination with a 130

pair of endless guides arranged in a vertical plane, said guides having vertically disposed straight portions and curved upper and lower portions, an endless chain operable in a plane
5 in the rear of said guides, a carrier mounted between said guides and secured to said chain, said carrier having a longitudinal member, spaced, transverse members pivoted upon said longitudinal member and a pair of wheels
10 arranged on each lateral side of each of said transverse members, the wheels of each pair being disposed to receive one of said guides between them, power driven means for operating said chain to traverse said carrier upon
15 said guides and a tray support rigidly supported on said carrier and projecting in front of said guides, said tray support being arranged to extend horizontally during the movement of said carrier between the straight
20 portions of said guides, and being inverted during movement over the curved portions of said guides.

In testimony whereof, I have hereunto signed my name to this specification.
